Primary Examiner — Elizabeth J Oswecki(74) Attorney, Agent, or Firm — Milton's IP/p.i.(57) CLAIM

The ornamental design for a holiday ornament, as shown and described.

DESCRIPTION

FIG. 1 is a perspective view of a holiday ornament showing our new design;

FIG. 2 is a front view of the design of FIG. 1.

FIG. 3 is a rear view of the design of FIG. 1.

FIG. 4 is a top view of the design of FIG. 1.

FIG. 5 is a bottom view of the design of FIG. 1.

FIG. 6 is a right side view of the design of FIG. 1.

FIG. 7 is a left side view of the design of FIG. 1; and,

FIG. 8 is another perspective view of the design of FIG. 1 shown in an open position.

The broken lines shown in the drawings represent portions of the holiday ornament that form no part of the claimed design.
